GEORGE HURN AND DANIEL HURN, OF LONDON, ENGLAND.

Letters Patent No. 86,755, dated February 9, 1869.

IMPROVEMENT IN THE MANUFACTURE OF MACHINE-BELTING.

The Schedule referred to in these Letters Patent and making part of the same.

To all whom it may concern:

Be it known that we, GEORGE HURN and DANIEL HURN, of London, England, have invented a new and improved Manufacture of Leather; and we do hereby declare that the following is a full, clear, and exact description thereof, which will enable others skilled in the art to make and use the same, reference being had to the accompanying drawings, forming part of this specification.

This invention relates to an improvement in the manufacture of driving-belts for machinery; and

It consists in the formation of the same from a weft and warp of leather, woven with selvages, without joints or splices, and with a double face or running surface.

In carrying out our invention, we employ continuous lengths of leather, cut into a continuous length or coil, by causing a knife, or suitable cutting-instrument, to pass over its entire surface, commencing, in practice, this cutting-operation, from the exterior of the said leather, hide, or skin, and passing the cutting-instrument along its edge, thus dividing a string or filament of the hide or skin, of one continuous length or coil, till the whole of the leather or hide is so divided.

This length of leather is then further prepared by longitudinal stretching, dampening, greasing, rolling, hammering, or such other equivalent operations as may be found necessary to remove the angles or curves formed in cutting the same continuously, and in one piece, from the hide.

In producing these continuous lengths of leather, we cause a knife, properly gauged, to traverse the exterior edge or perimeter of the hide spirally to the centre, thus cutting the entire hide into one continuous string or band, suitable for use, as above specified.

By this method of cutting, we are enabled to obtain, from a single skin or hide, a thread of leather two thousand (2,000) feet or more in length, in one piece.

The pieces, so cut, are woven upon any suitable

loom, with a warp of leather or vegetable fibre, into a variety of fabrics, such as driving-belts, harness-strips, window-shades, &c.

Where a driving-belt is woven, it will be noticed that, from the extreme length of the leather strips, the belt can be made sufficiently long, without joints or splices, to accommodate any machinery, and also that both sides constitute running surfaces.

By referring to the accompanying drawings, the manner of cutting the continuous strip will be seen at Figure 1, A being the uncut portion of the leather, and B, the strip, as partially cut. The dotted lines show the spiral path of the knife.

Figure 2 is a section of fig. 1, through the line *a a'*.

Figure 3 shows a hide from which wider strips are cut than in fig. 1.

Figures 4 and 5 represent the leather strips, arranged in hanks or skeins for use, fig. 5, being a transverse section of fig. 4.

Figure 6 represents leather webbing, formed by weaving with a warp and filling of leather or vegetable fibre.

Figure 7 represents a coarser specimen of weaving, for driving-belts and other fabrics. If found desirable, the hair may be left upon the hide.

Having thus described our invention,
What we claim as new, and desire to secure by
Letters Patent, is—

As a new article of manufacture, a driving-belt for machinery, formed from a weft and warp of leather, woven with selvages, without joints or splices, and with a double face or running surface, as herein shown and described.

The above specification of our invention signed by us this 29th day of July, 1867.

GEORGE HURN.

DANIEL HURN.
